ART OF DETERGING RADIATORS

Application filed December 17, 1930. Serial No. 502,956.

This invention relates to the art of deterging radiators, and has for an object to provide improved means for expelling from radiators employed in conjunction with automotive vehicles and the like, the several accumulations formed within said radiator.

A further object of the invention is to provide a receptacle into which a radiator may be introduced and to which, in such receptacle, may be attached the necessary facilities for carrying out the art which will be hereinafter more fully explained.

A further object of the invention is to introduce into a radiator a solution of detergent material which will cause the sediment and other accumulations within the radiator to separate from the walls of the radiator and then to introduce suddenly and violently air under pressure to expel the detergent solution, together with the accumulated deposits.

A further object of the invention is to provide steps in the art of deterging a radiator, which consists in introducing water in a heated condition into the radiator to fill the said radiator to capacity, evacuating the radiator, filling with a detergent solution, permitting the detergent solution to stand for a sufficient length of time to liberate the accumulations from the walls of the radiator, and then shocking and expelling the detergent solution by the sudden concussive admission of air under pressure to form substantially an explosion within the radiator to expel the solution and dislodge any still clinging accumulation from the walls or cells of the radiator.

The invention is directed to other objects and possesses other features of novelty and advantage, some of which, together with the foregoing, will be hereinafter more fully set forth.

In the drawings:

Figure 1 is a view of an apparatus for carrying into effect the art shown in front elevation.

Figure 2 is a view of the apparatus shown in top plan.

Figure 3 is a sectional view taken on line 3-3 of Figure 1.

Figure 4 is a view of a nozzle in elevation, showing a section of hose attached thereto, and

Figure 5 is a detailed view of the drain from the chamber. 55

Like characters of reference indicate corresponding parts throughout the several views.

The art which forms a part of the present invention may be carried out by the use of 60 a great variety of mechanical devices, or with only the most rudimentary of such mechanical devices.

The showing in the drawings of a complete installation for carrying out and practicing the art is no limitation upon the invention, and is merely an illustration of a convenient and fully equipped installation for the purpose. 65

It comprises a tank 10, preferably having inclined sidewalls so that the rear wall 11 is higher than the front wall 12. 70

The tank thus constructed is preferably covered over the greater portion of its area, leaving, however, an opening, as indicated 75 at 13, for access thereto. The cover may be of any type desired.

A section 14 is shown in the drawings as being rigidly attached to the tank 10 with the section 15 hinged thereto by the hinges 16. This, however, may be varied as occasion may make necessary or desirable. 80

Located somewhere adjacent to the tank 10 is a reservoir 17 which may be of substantially and usually the ordinary stand boiler 85 type with an inlet 18 for water, and a heater, indicated as a gas heater, 19.

Also located adjacent to the tank 10 is a second reservoir 20 which may be similar to the reservoir 17 and is provided with an inlet 21 controlled by a valve 22 for controlling the flow of water from the reservoir 17 into said reservoir 20. Provision is made for heating the reservoir 20, a gas pipe and burner 23 being indicated at Figure 1. 90

Also, at some convenient place an air reservoir 24 is provided. As shown in the drawings, the reservoirs 17 and 20 are respectively supported upon brackets 25 and 26, and the reservoir 24 supported by straps 100.

27 so that the entire device is an organized structure.

It is not, however, necessary that the several reservoirs be physically attached to the 5 tank, as they may be otherwise attached, as convenience may make desirable.

Extending into the opening 13 is a pipe 28 which is fitted with a nozzle 29 to be hereinafter more fully described. The pipe 28 is 10 connected through a pipe 30 controlled by a valve 31 from the air reservoir 24.

A pipe 32 communicates also with the top of the water reservoir 17 and is controlled by a valve 33, making connection with the 15 pipe 28 through a coupling 34. A pipe 35 extends from the chemical reservoir 20 and also makes connection with the pipe 28 after passing through a control valve 36.

The nozzle 29 is provided with a semi-spherical end 37, as shown in detail at Figure 4, and a section of flexible tubing or hose 38 is attached thereto, covering the semi-spherical part and the perforations 39 therein.

25 The hose section 38 is secured upon the nozzle 29 by the hose clamp 40. This section of hose 38, as shown at Figure 3, is of sufficient length and flexibility to be bent into the necessary angle to make connection 30 with the normal outflow connection 41 of the radiator 42. The connection 43 of the radiator is the connection normally at the top, the filling cap 44 indicating such top position.

A cap 45 is provided for closing the connection 43 and the usual overflow pipe 46 is shown as extending below the lower end of said radiator.

In operation, the detergent material is introduced into the reservoir 20 through the 40 filler opening 47 and water admitted thereto through the pipe 21 to form a solution of the necessary strength. The solution in the reservoir 20 is under pressure of air through the pipe 48 from the air reservoir 24, the 45 water in the reservoir 17 being under pressure of the normal water supply.

The radiator 42, being removed from the vehicle, is laid into the tank upon the strips or cleats 49 to support it off the bottom of 50 the tank. The radiator cap at 44 is now put in position and the hose section 38 attached to the lower connection 41.

Hot water from the reservoir 17 is now admitted through the pipe 32 by the manipulation of the valve 33 to fill the radiator, such filling being indicated by overflow at the 55 overflow pipe 46. The water is maintained in the radiator until the radiator has reached a temperature substantially equivalent to 60 boiling water or to water at very high temperature.

Air is now admitted through the valve 31 to expel the water from the radiator, or the greater part thereof, and the air valve being closed, solution from the reservoir 20

is admitted by the manipulation of the valve 36.

The amount of this solution admitted depends upon the strength of the solution, but it is not intended that the solution shall be 70 so weak as to require the entire radiator to be filled with the solution of reservoir strength.

When an amount indicated by the drop of the glass 49 indicates introduction of a sufficient amount, the valve 36 is closed, the valve 33 again opened and water admitted to complete the filling of the radiator. Thus filled, it is allowed to stand for a short time, which may be from one minute on to any desired length of time, but a very short period of time will usually suffice.

The normal inlet fitting 43 is now closed by the cap 45 and the filler opening 44 opened. The valve 31 is now suddenly opened wide 85 so that air under pressure from the tank 24 will pass through the nozzle 29 and the perforations 39 through the hose section 38 to the radiator, and will violently and concusively shock and expel all of the fluid and solution within the radiator, together with the deposits which have been loosened and separated from the walls of the radiator by the detergent solution, as well as liberating and separating and discharging others not 90 yet completely separated.

The employment of this air concusively under pressure, suddenly admitted in considerable volume and great force to shock the radiator parts, is believed to be the controlling step in the art. It is, however, necessary that the air, as it enters the hose pipe 38, shall be broken up to form air bubbles in the liquid as thereby a reverberatory effect is produced and it is therefore found desirable to employ perforations 39, as shown in the semi-spherical part 37 of the nozzle.

It will be noted that one row of perforations is practically covered in normal position by the hose section 38. When introducing water, the solution, or even air under normal conditions into the radiator, the outer row of perforations is not employed as it is covered by the flexible hose section 38. At the final inlet of the air, however, when it is introduced in the radiator, in great volume and under great force, the force through the perforations expands the hose pipe 38, so that all of the perforations are employed for the air and the volume of air is thereby not diminished.

Of course, after the detergent solution has been expelled from the radiator, water is further employed from the reservoir 17 for the purpose of washing out any solution which may remain and further use of air pressure may be employed and be repeated if found necessary or desirable.

Of course, the invention herein illustrated may be modified in various ways without de-

parting from the invention herein set forth and hereinafter claimed.

The invention is hereby claimed as follows:

- 5 1. The art of deterging a radiator, consisting in filling the radiator with a liquid, and then shocking and evacuating the contained liquid violently by the sudden introduction of a large volume of air under high pressure, said air being separated into several jets 10 as it is so introduced.
- 15 2. The art of deterging a radiator, consisting in filling a radiator with a liquid, and then producing a violent concussive expulsion of the liquid, by the introduction of numerous jets of air under pressure simultaneously to form a bubbling intermixture of air and water throughout the radiator.
- 20 3. The art of deterging a radiator, consisting in introducing therein water at a high temperature for the purpose of heating and expanding the radiator, expelling the heated water and suspended material from the radiator, introducing at a high temperature into the radiator a detergent solution, permitting 25 the detergent solution to stand a sufficient length of time to perform a cleavage of the deposits from the walls of the radiator, introducing concussively air under high pressure to violently shock and expel the detergent solution from the radiator, and flowing water therethrough to wash out the remaining solution and deposits.
- 30

In testimony whereof I have signed my name to this specification.

35 JOSEPH CARMIN.
